UNITED STATES PATENT OFFICE.

BERNARD BEN LOWENSON, OF LOUISVILLE, KENTUCKY.

STENCIL.

SPECIFICATION forming part of Letters Patent No. 373,838, dated November 29, 1887.

Application filed February 10, 1887. Serial No. 227,191. (Specimens.)

To all whom it may concern:

Be it known that I, BERNARD BEN LOWENSON, a citizen of the United States, residing at Louisville, in the county of Jefferson and State 5 of Kentucky, have invented a new and useful Improvement in Stencils, of which the following is a specification.

My invention relates to an improvement in stencils; and it consists in a pair of stencil- 10 plates, one of which is provided with the pattern, letters, or characters cut out in detached parts, and the other provided with openings 15 adapted to register with the spaces separating the parts of the pattern, letters, or characters in the primary plate, whereby complete characters, patterns, or letters may be marked, as will be more fully set forth hereinafter, and particularly pointed out in the claim.

In the drawings, Figure 1 is an elevation of 20 a primary stencil-plate. Fig. 2 represents the characters inscribed by means of the primary plate. Fig. 3 is an elevation of the secondary stencil-plate. Fig. 4 represents the completed characters formed by the use of two plates.

25 A represents a primary stencil-plate in which a pattern, letters, or characters are cut out, the said pattern, letters, or characters being necessarily made in detached parts in the usual manner. When the said primary stencil- 30 plate is laid upon a surface to be printed and a brush charged with ink or color is passed over the said plate, letters or characters are formed which are not entire, but are composed of parts separated by intervening spaces, 35 as shown at Fig. 2.

In order to enable complete letters, characters, or patterns to be stenciled, I provide a secondary stencil-plate, B, which is of the same size as the primary plate and has openings C, which register with the open spaces 40 left in the characters marked by the primary plate, as shown at Fig. 3. When the primary

stencil-plate has been removed after marking the disconnected patterns or characters, the secondary stencil-plate is carefully placed 45 upon the surface to be printed, and is so adjusted thereon as to cause the openings C to fall upon the spaces between the parts of the characters or letters marked by the primary plate. The brush is then passed over the sec- 50 ondary plate, and thereby color or ink is applied to the blank spaces in the letters or characters, thus completing them, as shown at Fig. 4.

If desired, the color applied to the second- 55 ary stencil-plate may be different from that used with the primary plate, thus forming chromatic letters or characters, or one or more colors different from that of the surface to be printed upon may be applied thereto 60 before using the stencil-plates to secure a like result.

I propose to make my stencil-plates of oil- 65 paper, sheet metal, or any other suitable material, and do not limit myself in this par- ticular.

Having thus described my invention, I claim—

The combination of the primary stencil-plate having the disconnected or fragmentary pat- 70 terns, letters, or characters and the secondary stencil-plate having the openings C, corre- sponding to the spaces between the parts of the characters, letters, or patterns cut in the primary plate, for the purpose set forth, sub- 75 stantially as described.

In testimony that I claim the foregoing as my own I have hereto affixed my signature in presence of two witnesses.

BERNARD BEN LOWENSON.
